UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

METHOD OF MANUFACTURING NOTE SHEETS.

Original application filed December 8, 1914, Serial No. 876,147. Patent No. 1,432,424, dated October 17, 1922. Divided and this application filed July 29, 1921. Serial No. 488,495.

The present invention relates to a method of making note sheets for musical instruments, more particularly note sheets bearing markings comprising informative indicia in addition to and co-related with note perforations. One kind of marking commonly used on note sheets is a more or less continuous line or other indication known as a dynamic line, the purpose of which is to indicate variations in the intensity of the playing of the notes represented by the note perforations.

The problem of applying informative markings to note sheets has been approached from a number of angles, none of which has heretofore proven so effective as the method forming the subject matter of applicant's present application which is a division of his Patent No. 1,432,424, granted October 17, 1922, for machines for use in the manufacture of perforated note sheets. One object of applicant's method is to produce a note sheet or a plurality of similar note sheets in a substantially continuous operation and coincident with a single operative manipulation of a so-called master or pattern sheet, although it is contemplated that in certain respects, the invention includes the making of a note sheet or a plurality of similar note sheets otherwise than coincident with a single operative manipulation of a single master or pattern sheet. However, where a pattern sheet is employed which embodies an instrumentality for controlling the making of an informative marking on the note sheet and also embodies a note perforation pattern, it is contemplated that both the marking and the perforating may take place to a certain extent concurrently. A further object of the invention is to apply the informative indicia marking to the note sheet in advance of the making of the note perforations therein so that a marking device or devices may be used more or less without interference with or interruption from the note perforating operation or the note perforations. With the foregoing and other objects in view, the improved method of the present application contemplates the making of note sheets having note perforations and informative indicia related thereto in which a moving note sheet is subjected to a marking operation and then, after a predeter-

mined increment of marking has been applied, the note perforations are made, the marking and the perforating thereafter being concurrent. One form of apparatus by means of which my improved method may be practiced is shown in the drawing accompanying the present specification, it being understood that said drawing represents merely diagrammatically an illustrative embodiment of suitable apparatus for the purpose. In said drawing,

Fig. 1 shows diagrammatically the entire 65 illustrative embodiment; and

Fig. 2 is a detached plan view of a detail on the line 2—2 of Fig. 1.

As shown in the drawings the illustrative mechanism comprises a pattern, means 70 for feeding the note sheet material to be perforated, and associated therewith a marking mechanism and a perforating mechanism.

The perforating mechanism and the pattern means for selectively controlling the perforating, and also the feeding mechanism for the note sheet material to be perforated, may be of any suitable type. The illustrative embodiment comprises a pattern or stencil sheet 2 and note sheet material 3. The pattern sheet is shown as provided with perforations 4 corresponding to perforations intended to be punched in the note sheet material 3 which may comprise a stack 85 of superposed sheets which may be punched collectively.

The pattern sheet 2 is mounted upon a spool 8 and may be fed in any practicable manner and wound, if desired, upon a take-up roll which is considered unnecessary to be shown in the drawing. For the purposes of the specific machine it is desired that the feed of the pattern sheet 2 be synchronized with the operation of the perforating mechanism and to illustrate diagrammatically one way in which this may be done, the pattern sheet 2 is shown as passing over a drum 9 which is geared with or otherwise synchronized with the perforating mechanism 100 as through gears 10, 10. The drum 9 is provided with teeth 11, 11, to engage uniformly spaced perforations 12, 12, in the margin of the pattern sheet 2. The cooperation of these teeth 11 with the perforations 105 12 (or any equivalent or substituted ex-

pedient) may insure predetermined successive relationships between the moving pattern sheet and the perforating mechanism and also the moving note sheet material.

5 The pattern sheet 2 exemplifies a prime controller of a punch selecting mechanism which may be of any practicable type. One suitable form of punch selecting mechanism comprises a tracker bar 15 provided with 10 vents to be opened by the perforations 4 of the pattern sheet. Each vent is connected by a duct—exemplified by the duct 16—with the controlling valves of a power pneumatic 18. As well understood in the 15 art, when the corresponding vent in the tracker bar 15 is opened by a perforation in the pattern sheet, suction is admitted to the power pneumatic 18 causing the latter to collapse. When thus collapsed the pneumatic 18 lifts a selector slide 20; but when the tracker vent is again closed, permitting the pneumatic 18 to expand again, the slide 20 is drawn downwardly to the position shown in the drawing by a spring 21.

25 It will be understood that there is a series of selector slides 20 corresponding each to one of the punches of the perforating mechanism. One complete set of selecting and punching devices is shown diagrammatically 30 in the drawing; and it will be understood that these parts are reduplicated as many times as may be necessary to provide for punching the desired number of rows of perforations.

35 The selecting mechanism comprises further a horizontally reciprocating cross head 22 carrying selector pins 23 which are so mounted as to slide lengthwise readily in the cross head 22. This cross head 22 is 40 connected by a link 25 with an eccentric upon the shaft 26 which shaft is rotated continuously during the operation of the machine, thereby reciprocating the cross head 22 and its gang of selector pins toward 45 and from the selector slides 20. A lever 28 fulcrumed at 29 bears at its upper end against the head of the selector pin 23 and is held in engagement with the selector pin head by a spring 30 which tends always to 50 rock the lever 28 in a contra-clockwise direction. The lower end of the lever 28 is pivotally connected to a selector bar 32 the right hand end of which in the drawing rests in a guide way in a vertically reciprocating cross head comprising the two connected parts 33, 34. The part 34 carries 55 a gang of punches 35 and the part 33 includes the punch driving bar 36.

The cross head 33, 34 is reciprocated vertically in appropriate guide ways by an eccentric upon the shaft 26, which is unnecessary to be shown. This suffices to illustrate that for each complete revolution of the shaft 26, the cross head 33, 34 is moved 60 downwardly and then upwardly through one

complete reciprocation. The punches 35 are carried sufficiently loosely in the cross head piece 34 to permit them to drop against the note sheet material 3 without perforating the same except when the selector bar 32 has 70 been moved far enough toward the right in the drawing so that the full width will be interposed between the driving bar 36 and a punch head, otherwise the punch may rise 75 into the notched end 32' and does not perforate the sheet material.

The punches 35 are arranged to slide vertically in a stripper bar 38 which overlies the note sheet material 3 supported at the 80 punching point upon a die 39.

With the described arrangement, when the cross head 22 is moved toward the left in the drawing, the lever 28 is permitted to rock slightly contra-clockwise and thereby to move the selector bar 32 toward the right. 85 If the selector slide 20 remains in the position shown, the movement of the selector pin 23 is arrested in such a position that the selector bar 32 cannot move far enough to be interposed in driving position between the punch 35 and the driving bar 36; but if the selector slide 20 has been lifted (by the opening of the corresponding tracker vent) the cut-out portion 40 of the selector slide 90 is thereby positioned opposite the selector pin 23, permitting a sufficient movement of the pin, the lever 28 and selector bar 32, to move the latter into driving position and cause its corresponding punch to be driven through the note sheet material 3. As will 95 be understood by those skilled in the art, the horizontal reciprocation of the selector cross head 22, and the vertical reciprocation of the punch cross head 33, 34, are relatively so timed that the cross head 22 is moved toward the left to position the various selector bars 32 appropriately to the perforations to be punched, preparatory to the descent of the cross head 33, 34 to drive the 100 selected punches through the note sheet material.

It is to be understood that the punch selecting and perforating mechanisms just described are merely illustrative and any suitable equivalent or substitute may be employed.

The note sheet material 3 may be fed relatively to the punching mechanism in any practicable manner. For instance, cooperating endless belts or chains 50, 52 may be provided having cross bars 53, 54 so disposed that a cross bar 53 and a cross bar 54 register with each other on opposite sides of the note sheet material 3 on the adjacent runs of the belts or chains, so as to grip the note sheet material between the cross bars with sufficient pressure to cause the note sheet material to accompany the belts or chains during their movement. As this feed mechanism is diagrammed in the drawings, the 110

belts or chains are driven intermittently by a pawl 56 engaging a ratchet 57 upon a shaft 58 of one of the pulleys for the belt or chain 50. Also fixed upon the shaft 58 is a gear 60 meshing with a gear 61 upon a shaft 62 for the lower belt or chain. The pawl 56 drives its ratchet 57 in a counter-clockwise direction and thereby through the gears 60 and 61 drives the two belts or aprons in the proper direction to feed the note sheet material 3 toward the right in Fig. 1 as indicated by the arrow.

The pawl 56 is reciprocated by a pitman 65 connected to an eccentric 66 upon the shaft 26, that eccentric being so disposed upon the shaft that the belts or chains 50, 52 remain at rest during the downward movement of the cross head 33, 34 to drive the punches; and when said cross head is moved upwardly, the eccentric 66 causes the note sheet material 3 to be advanced through one feed step.

The foregoing description has pertained to the mechanism for selecting the punches and causing them to perforate the note sheet material. Hereinafter will be described a marking mechanism adapted to cooperate with the above described apparatus but which may be employed separately if desired.

A marking mechanism embodying features of this invention may be employed in various ways and for marking any of a number of different marks or indications upon a note sheet, but for purposes of explanation it will suffice to describe the use of the marking mechanism in placing a so-called "dynamic line" upon the note sheet material. This dynamic line is ordinarily a line or a succession of marks which meanders along the length of the sheet, the distance between any given point in the line and an edge of the sheet indicating a degree of loudness of playing.

In the illustrative apparatus, the marking is done by a pen arranged to rest upon each sheet of the note sheet material and to be moved transversely of the sheet during the feeding movement of the sheet, the composite of these two movements producing the meandering dynamic line. To best suit this sort of marking, wherein the pen preferably rests upon the sheet and remains in contact therewith—and as well to suit the general cooperative assembly of the parts—it is preferred to have the marking take place before the note sheet material is perforated; otherwise the perforations might interfere with the movement of the pen or other marking devices. While this is not indispensable, the illustrative apparatus is so arranged that the marking devices act upon the note sheet material at a point between the source of supply of the note sheet material and the punching point.

The illustrative dynamic line intended to be drawn by the marking apparatus is supposed to be made upon the face of the note sheet—i. e. that surface of the sheet which is exposed to the view of the operator when the finished note sheet is used in an automatic player-piano or the like. The punches, however, are preferred to be forced through the note sheet material from the reverse side of the sheet toward the face thereof. The punching operation, especially when the punches are slightly dulled, is likely to leave a slight burr or roughness at the edges of a perforation on that surface of the sheet opposite the punches and it is preferred to have this burr project from the face of the finished sheet so that the reverse side of the sheet which contacts with the tracker bar in the automatic instrument shall be entirely smooth. For these reasons, while it is desired to have the marking devices positioned to operate upon the face of the sheet, it is further desired to have the punches operate upon the opposite or reverse side of the sheet. The illustrative apparatus is organized to suit this purpose. Although, when the note sheet material 3 reaches the punching point, it may comprise a stack of as many as fifteen or twenty individual sheets, the present drawings, for the sake of clearness, show only two such sheets A and B. Each sheet A, B is mounted upon a spool 70, and each sheet passes from its spool 70 around a roller 71 which is mounted for vertical movement in bearings 72 shown diagrammatically. The shaft of each roller 71 has connected to it means, such as a spring 73 for exerting a yielding pressure upon the roller in opposition to the pull upon the roller exerted by the sheet as it is fed over the roller. The illustrative mechanism (the belts or chains 50, 52) for feeding the note sheet material has been described as feeding the sheets intermittently so that a more or less jerky movement is imparted to them. The shocks of the intermittent feed steps of the respective note sheets are desirably taken up or absorbed by the springs 73, 73. Similar means performing the functions of these illustrative shock absorbers may be located at any desired point along the path of travel of the note sheets.

From its roller 71 the sheet A passes over an idle roller 75 adjustably mounted in its bearings for purposes presently described. Thence the sheet A passes over an idler 76 and a second idler 77 (also adjustable in its bearings.) The run of the sheet between the idlers 76 and 77 is preferably substantially horizontal and the marking devices are preferably arranged to mark that portion of the sheet which lies between the idlers 76 and 77. From the idler 77 the sheet A passes over another idle roller 78 to an idler 79 at which point the

sheet A meets the sheet B so that the two (together with others if desired) may be fed collectively to the punching point. The sheet B passes around idlers 85, 86, 87 and 88 corresponding to the described idlers for the sheet A. The idlers 85 and 87 are adjustable in their bearings.

It is assumed that the dynamic line is to be exactly the same on both of the sheets A and B and that upon each sheet the dynamic line is to be positioned in a precise predetermined relationship with the perforations in the sheet. To suit these purposes it is important to predetermine accurately a certain length of note sheet material between the exact marking point and the punching point. In other words, if the length of the sheet A between its marking device and the punches were greater than the length of the sheet B between its marking device and the punches, the dynamic line and perforations on the former when finished would have a different relationship from that of the dynamic line and perforations upon the sheet B when finished. Therefore means exemplified by the provision for adjusting the idlers 77 and 87, is supplied for adjusting the lengths of the sheets. For example, if the roller 77 is adjusted toward the left in the drawing, a greater length of note sheet is thereby caused to intervene between the roller 77 and the punching point, and vice versa if the roller is adjusted toward the right. The rollers 75, 77, 85 and 87 are shown as provided with horizontally slotted bearings 90 in which the rollers may be adjusted, any of the well known expedients being employed to hold the roller shafts in their adjusted positions.

To suit the organization of the punching mechanism, the note sheets are fed to the punches with their faces down in order to present their rear sides toward the punches. Hence the illustrative arrangement of the rollers 75, 76 and 77 serving to reverse the sheet to present its face upwardly exposed to receive a marking pen.

The sheet A is acted upon by a marking device 95 which may be of any suitable type as for instance a siphon pen. A similar marking device 96 is provided for the sheet B and these may be duplicated for as many other sheets as are desired to be marked concurrently. Each pen is mounted upon a holder 98 which may be in the form of a sleeve pinned to a shaft mounted upon a horizontal axis in an arm 99 fixed upon a vertically disposed shaft 100. Upon the same shaft is pinned an arm having at one end a weight 101 and at its other end a lug 102. The weight arm and the pen holder 98 being pinned to the same shaft, the weight tends to hold the pen down against the note sheet material and by depressing lug 102 the pen may be lifted off the sheet. The pen

or other marking device is thus provided with means for moving it toward and from the sheet and this means may be appropriately operated automatically so as to make individual marks upon the sheet or to move the pen onto the sheet and permit it to rest there to make a continuous line or a line interrupted as desired.

For the purposes of the specific type of continuous dynamic line assumed to be desired in the present instance, the means for moving the marking device toward and from the sheet is automatically operated to move the pen into marking position against the sheet at the time the dynamic line is desired to begin, and to withdraw the pen from the sheet when the dynamic line has been finished.

The mechanism for this purpose comprises a vertically disposed slide rod 103 having fingers 104, 104 respectively to cooperate with the lugs 102 on the pen carrying shafts. The upper end of the slide rod 103 is secured to the movable board of a motor pneumatic 106 which through appropriate valves is arranged to be exhausted upon the opening of a tracker vent 107, a duct 108 connecting said vent 107 with the valve mechanism for the pneumatic 106. In the illustrative apparatus the vent 107 is arranged for cooperation with the same pattern sheet which constitutes an element of the punch selecting mechanism but this is not essential. In the specific apparatus the vent 107 is intended to be closed when the pattern sheet 2 is first introduced and preparatory to the beginning of the dynamic line, and to be opened at or just before the instant when the dynamic line is to be begun. The illustrative manner in which this is accomplished will be more fully described hereinafter.

The pen carrying rod 100 is mounted between two rocker arms 110, 111 mounted upon a common axis, the arm 110 being pivotally supported upon a bracket 112 and the arm 111 upon a bracket 113. As shown in Fig. 2, the arm 111 has a finger 115 connected to a link 116 and also to a spring 117. As shown in Fig. 1, the link 116 connects the finger 115 with the movable board of a pneumatic 120. By collapsing the pneumatic 120 more or less, the link 116 is moved toward the left in Figs. 1 and 2, thereby rocking the finger 115 and arm 111 in a contra-clockwise direction to move the pens transversely of the direction of feed of the note sheet material. When the pneumatic 120 is permitted to expand, the spring 117 rocks the finger 115 and arm 111 in a clock-wise direction to move the pens in the opposite direction transversely to the direction of feed of the note sheet material. Thus by varying the degree of exhaust in the pneumatic 120 the pens may be con-

trolled so that the result of their transverse movement on the note sheet and the feeding movement of the note sheet shall produce the meandering dynamic line. The degree 5 of exhaust in the pneumatic 120 may be varied in any practicable manner.

For example, a duct 121 connects the pneumatic 120 with a cylinder 122. The cylinder has a port 123 to the atmosphere 10 and is also connected by a duct 124 to an exhaust chest 125. A duplex piston having the parts 126 and 127 has a snug but sliding fit in cylinder 122 and the stem of said piston is connected to a lever 128 fulcrumed at 129, the lower end of which is pivoted at 130 to the link 116. The cylinder 122 is connected by link 132 with an extension 133 of the movable board of a pneumatic 134 and a part of the same extension 133 on the opposite side of the hinge of the pneumatic 134, is connected to a slide 136 fitted in the tracker 15 and carrying a tracker vent 138 connected by a duct 139 with the interior of the pneumatic 134. The pneumatic 134 is arranged to be exhausted 20 past a bleed 140 through a duct 141 communicating with the exhaust chest 125. A spring 142 tends to expand the pneumatic 134.

25 To control the operation of the described apparatus, the pattern sheet 2 or its equivalent or substitute is provided with means co-operating with the tracker vent 138 and there-through to govern the degree of exhaust in the pneumatic 120 so as to move the pens as desired transversely of the direction of travel of the note sheet.

As one arrangement for operating on the tracker vent 138, the margin of the pattern 40 sheet 2 is cut along a meandering line corresponding in shape to the meandering dynamic line desired to be marked upon the note sheet. In other words the edge of the punch selecting pattern sheet may be cut in 45 the shape of a pattern to predetermine the undulations in the dynamic line.

The free end of the pattern sheet 2 is preferably left of full width so that when initially secured to the takeup roll, the advance 50 end of the pattern sheet will close the tracker vent 107. Under these circumstances the pneumatic 106 is in expanded position, the slide rod 103 is held in its lowermost position by gravity and thereby the pens are 55 held away from the note sheet material.

At this time also the introduction of the pattern sheet may have closed the tracker vent 138. The immediate effect of this is to cut off atmosphere from the pneumatic 60 134 which, being then exhausted past the bleed 140, is collapsed. But, in this collapsing movement it draws the slide 136 toward the left in Fig. 1 and presently the vent 138 is partially uncovered so that an atmospheric bleed is established to the pneu- 65

matic 134. The collapse of the pneumatic 134 will continue until this pneumatic bleed suffices to balance the exhaust past the bleed 140 whereupon the pneumatic 134 will come to rest in a partly collapsed position. 70

Assuming that the foregoing has occurred upon initial introduction of the pattern sheet to the machine, the feed of the sheet presently carries to the tracker the advance end of the cut-away portion which constitutes 75 the dynamic line pattern. When this occurs the cut-away portion leaves open the tracker vent 107 which produces a collapse of the pneumatic 106 thereby lifting the slide rod 103 and permitting the weights 101 to move 80 the pens down upon the note sheets and to hold them there in marking position. At the same time the cut-away margin of the pattern sheet 2 opens the tracker vent 138 and disturbs the balance between the suction 85 bleed and the atmospheric bleed to the pneumatic 134, by increasing the atmospheric bleed and thereby permitting the pneumatic 134 to expand until, in that movement of the slide 136 toward the right in Fig. 1, the vent 90 138 is again partially closed by the margin of the pattern sheet so as to restore the balance of the two bleeds. As the pattern edge of the sheet 2 meanders across the tracker bar, the described arrangement of 95 bleeds so varies the degree of exhaust in the pneumatic 134 that its collapsing and expanding movements cause the tracker vent 138 to follow accurately the undulations of 100 that pattern edge; and in this manner those 100 undulations cause the corresponding movement to take place in the extension 133 of the movable board of the pneumatic 134. Thus the cylinder 122 is caused to reciprocate in an axial direction with a motion exactly corresponding to the degree of variation in 105 what may be called the amplitude (measured transversely of the pattern sheet 2) of the pattern edge. If it were desired to employ a pneumatic 134 of sufficient mechanical 110 power directly to move the pens and the parts upon which they are mounted, there might be a direct mechanical connection between the extension 133 and the rocking support for the pens. It is preferred, however, 115 to use a pneumatic 134 of low power which shall be more readily responsive to the described arrangement of bleeds, and to use in cooperation therewith a working pneumatic of higher power and for this purpose 120 the pneumatic 120 is used.

To permit freedom of movement of the cylinder 122, the ducts 121 and 124 are made freely flexible.

In the position shown in Fig. 1 the duplex 125 piston 126, 127 is so positioned in the cylinder 122 that both the atmosphere port 123 and the exhaust port 124 are closed. If under these conditions, the pneumatic 134 collapses slightly, the cylinder 122 will be 130

- 5 moved toward the right and thereby, while the atmosphere port 123 is still held closed, the exhaust port 124 will be open at least to a slight extent. Thereby the pneumatic 120 will be exhausted to some extent and will collapse. This collapsing movement rocks the lever 128 clockwise and moves the piston 126, 127 toward the right causing it to follow the movement of the cylinder. This movement of the piston tends to close the exhaust port 124 and does in fact close it if the described collapse of the pneumatic 134 ceases. In fact, the piston 126, 127 follows the movement of the cylinder 122 until finally the 10 piston resumes the position shown in the drawing closing both the atmosphere and the exhaust ports of the cylinder. Thereupon the degree of exhaust in the pneumatic 120 is held constant temporarily until some further movement of the cylinder 122 takes place. If then the pneumatic 134 expands somewhat, moving the cylinder 122 toward the left, the atmosphere port 123 is opened, the pneumatic 120 is permitted to 15 expand, and the lever 128 again rocked, this time contra-clockwise, to cause the piston to follow the cylinder movement toward the left until the atmosphere port is again closed.
- 20 30 It will be obvious to those skilled in the art that the described construction and arrangement of the cylinder 122 and piston 126, 127 provides a sort of relay by which the movements of the preferably low powered pneumatic 134 may be reproduced in a preferably high powered pneumatic 120, so that the latter may be caused to rock the pen supports in a manner exactly corresponding to the movement of the tracker vent slide 136.
- 25 40 45 The dynamic line pattern edge, or its equivalent or substitute, is of course laid out to represent a resultant movement comprising as its components the feed movement of the pattern sheet, and the transverse movement of the tracker vent slide 136. This component in a direction transverse to the pattern sheet is transmitted by the described apparatus to the pens themselves and their movement transverse the note sheet combines with the feeding movement of the note sheets to produce the resultant dynamic line.
- 50 55 60 With the illustrative arrangement shown in Fig. 1, the amplitude of undulations of the pattern edge of the sheet 2 produces on the note sheet a somewhat greater amplitude of undulations in the dynamic line measured transversely of the note sheet. The slide 136 and the link 132 are connected to the lever provided upon the movable board of the pneumatic 134, at substantially equal distances from the hinge of the pneumatic constituting the lever's fulcrum—therefore the extent of movement of the slide 136 (which 65 exactly follows the amplitude of the pattern

undulations), produces an equal extent of movement of the link 132 and cylinder 122. The effective movement of the piston 126, 127 is the same as that of the cylinder 122; and the extent of this movement of the piston produces an equal extent of movement of the link 116, because, as shown, the fulcrum of the lever 128 is located midway between the respective points of attachment of the piston and the link 116. Therefore the extent of movement of the link 116 is to all intents and purposes equal to the amplitude of the undulations in the pattern margin. Thus the oscillations of the finger 115 (see Fig. 2) are equal in extent to the amplitude of undulations of the pattern edge; but, as shown, the distance of the pen point from the fulcrum 100 upon which it rocks in its transverse movement, is greater than the distance from that fulcrum 100 to the point of attachment of the link 116, and therefore the extent of movement of the pen is greater than the extent of movement of the tracker vent slide 136. In other words the amplitude of undulations of the dynamic line on the note sheet is greater than that of the pattern edge.

Thus the variations in amplitude of the dynamic line are made to correspond exactly with the variations in the pattern edge, but the amplitudes themselves are greater in the first case than in the last. In other words, the meandering of the dynamic line on the note sheet covers a wider area than the meanderings of the pattern edge on the pattern sheet. If desired, however, the relation between the amplitudes of pattern edge undulations and dynamic line undulations may be adjusted by moving the fulcrum 129 of the lever 128. For instance, if the fulcrum 129 is moved downwardly (in the slot of the lever 128 provided to permit that adjustment) the amplitude of undulations of the dynamic line is diminished and may be made equal to those of the pattern edge, or otherwise varied as desired.

As will appear to those skilled in the art, the pattern edge on the sheet 2 is merely the illustrative form of prime controller for marking devices, and it may or may not be used in conjunction with a prime controller, such as the pattern sheet 2, for punch selecting mechanism or the like. The specific pattern sheet 2 however, serves as a unitary prime controller for both the punch selecting mechanism and the marking mechanism; and is particularly adapted to provide for marking the note sheet material before it is perforated.

In the usual finished note sheet it is important that each point in the dynamic line be positioned lengthwise the sheet in a definite relation to the note playing perforations. For instance, it is ordinarily desired that any given group of note perforations

shall reach the tracker at approximately the same time that those parts of the dynamic line pertaining to those note perforations occupy the field of vision of the operator.

For convenience in description it may be assumed that the advance end of a dynamic line to be marked by the apparatus of the drawing is desired to be placed in the same line transverse the note sheet, with the advance end of the initial note perforation therein. But as already described, after the advance end of the dynamic line has been marked on the note sheet material, the latter is obliged to travel from the pens 95, 96 through a substantial distance to the punches 35, before the note sheets are presented in position to receive note perforations aligned with the advance end of the dynamic line. To suit this situation, the illustrative apparatus is so organized that the marking of the dynamic line is begun and continues for a considerable period, and until the advance end of the dynamic line reaches the punching point, before any note perforations are punched. This is provided for by locating the advance end 160 of the pattern edge of the sheet 2 a certain distance in front of the advance edge 161 of the initial note perforation, said distance corresponding to the distance which the note sheet material is obliged to travel from the marking point (at the pens 95, 96) to the punching point. Of course, the distance between the advance end 160 of the pattern edge and the advance end 161 of the first note perforation will depend largely upon the relative speeds of feeding movement of the pattern sheet 2 and the note sheet material—the desideratum being merely that during the time the pattern sheet 2 is fed through the distance between the points 160 and 161, the note sheet material will have been fed through the distance between the marking point and the punching point.

Thus, it will appear from the foregoing that my improved method may be practiced in connection with a marking mechanism and a perforating mechanism, so co-ordinated as to produce note sheets having note perforations and informative markings located thereon in predetermined relationship; and this co-ordination of the two mechanisms may be governed by a single prime controller such as the pattern sheet 2, although this is not indispensable.

It is to be understood that this invention is not limited to the specific construction, organization and mode of operation shown in the drawings and hereinbefore described for illustration. On the contrary, the invention may be variously embodied and the specific construction and organization may be variously modified. Furthermore it is not necessary that all the features of the

invention be used conjointly since they may be used to advantage separately.

I claim as my invention:

1. The method of making note sheets for musical instruments by marking informative indicia on and making note perforations related thereto in said note sheets which includes moving said note sheet, subjecting said moving note sheet to a marking operation and then, after a predetermined increment of marking has been effected, beginning the making of note perforations at a point properly related to the informative indicia previously marked on said sheet. 70 75

2. The method of making note sheets for musical instruments by marking a dynamic line on and making note perforations related thereto in said note sheets which includes moving said note sheets, progressively marking the moving sheets, and then, after a predetermined interval from the beginning of said marking operation progressively making the note perforations at points properly related to the dynamic line already formed, and continuing the marking and perforating concurrently. 80 85 90

3. The method of making note sheets for musical instruments by marking informative indicia on and making note perforations related thereto in said note sheets which includes moving said note sheets, progressively marking an increment of note sheet, and then concurrently and progressively marking and perforating said sheet, said perforations being located in proper relation to the informative indicia previously marked on said sheet. 95 100

4. The method of making note sheets for musical instruments from a pattern sheet having a pattern edge which includes making on said sheets during longitudinal movement thereof a marking corresponding in direction variation to said pattern edge and subsequently making note perforations in the sheets in predetermined relation to the direction variations of said marking. 105 110

5. The method of making note sheets for musical instruments from a master sheet embodying a dynamic line pattern and a note perforation pattern which includes making on said sheets during longitudinal movement thereof a dynamic line marking having direction variations predetermined by the dynamic line pattern, and making note perforations in said sheets in predetermined relation to the direction variations of said dynamic line marking. 115 120

6. The method of making note sheets for musical instruments which includes applying a dynamic line marking to individual sheets simultaneously, assembling said marked sheets in superposed relation and with the corresponding convolutions or portions of the dynamic line markings of the 125 130

several sheets in register through the stack of superposed sheets, and perforating the assembled sheets.

7. The method of making note sheets for musical instruments from a master sheet embodying a dynamic line pattern and a note perforation pattern which includes making on said sheets during longitudinal movement thereof a dynamic line marking having direction variations predetermined by the dynamic line pattern and note perforations in said sheets in relative positions predetermined by said note perforations.
- 10 8. The method of making note sheets for

musical instruments which includes applying a dynamic line marking to individual sheets simultaneously superposing said marked sheets with the corresponding variations of the dynamic line markings of the several sheets in register through the stack of superposed sheets, and making note perforations in the sheets while in superposed relation.

In testimony whereof, I have signed my name to this specification this 19th day of July, 1921.

CHARLES F. STODDARD.
